UNITED STATES PATENT OFFICE.

ASA FRANK HOUCK, OF EASTON, PENNSYLVANIA.

STOVEPIPE-ANCHOR.

1,132,347.

Specification of Letters Patent. Patented Mar. 16, 1915.

Application filed October 3, 1914. Serial No. 864,890.

To all whom it may concern:

Be it known that I, ASA F. HOUCK, a citizen of the United States, residing at Easton, in the county of Northampton and State of Pennsylvania, have invented new and useful Improvements in Stovepipe-Anchors, of which the following is a specification.

This invention relates to stove pipe anchors, and particularly to means for securing a thimble and pipe within a flue opening, whereby casual displacement of the stove pipe and thimble will be prevented.

The primary object of the invention is to provide a clamping device which, upon the application of the pipe and thimble, may be adjusted from an external point to bring a clamping device upon the thimble into engagement with the pipe and wall of the flue opening, whereby the pipe and thimble will be held firmly against relative movement or displacement.

A further object of the invention is to provide a simple, reliable and efficient construction of clamping device and adjusting means which may be readily and conveniently applied to the thimble for use.

The invention consists of the features of construction, combination and arrangement of parts herein fully described and claimed, reference being had to the accompanying drawing in which:—

Figure 1 is a horizontal section through a stove pipe, thimble and flue wall, showing the application of the invention. Fig. 2 is a fragmentary elevational view looking toward the clamp from the interior of the thimble. Fig. 3 is a side elevation showing the clamp in position to permit insertion or withdrawal of the thimble. Figs. 4 and 5 are detail views of the clamp and coupling plates, respectively. Fig. 6 is a view in side elevation of the thimble flange removed from the pipe.

Referring to the drawing, 1 designates a flue or chimney provided with the usual flue opening or passage 2, within which is located the end of a stove pipe 3 encompassed by a thimble 4 provided with a flange or joint closing ring 5. The thimble is provided with a T-shaped slot 6 to receive a clamping member or cross piece 7 upon one end of a clamping plate 8, said member or head 7 being adapted for engagement with the thimble 4 when the clamping plate is in a predetermined position.

The member or head 7 is offset from the plane of the plate 8 and connected therewith by a reduced portion or shank 9, extending through the cross portion of the slot 6 and co-operating with the member 7 to produce a T-shaped coupling and clamping member adapted to be moved into and out of clamping engagement with the stove pipe.

The plate 8 is of rectangular or oblong rectangular form and at its end opposite the head 7 is provided with spurs or biting projections 10 bent inwardly at the opposite sides thereof and adapted for engagement with the wall of the flue opening 2 to hold the clamping plate against outward movement.

It will be evident from the foregoing description that the T-shaped coupling and clamping head formed by the parts 7 and 9 may be engaged with the thimble by first disposing said head longitudinally of the thimble and passing it through the longitudinally extending portion of the slot 6, after which by imparting a quarter revolution to the clamping plate and disposing the T-shaped head in the cross portion of said slot the clamping plate will be quickly mounted for swinging movement in a direction longitudinally of the thimble and at the same time will be locked against relative displacement. The construction is also such that the offsetting of the portion 7 in the manner described adapts the same by reverse swinging movements of the clamping plate to be moved into and out of clamping position with relation to the pipe 3, as will be readily understood.

The clamping plate 8 is formed with an elongated slot 11 to receive a T-shaped coupling head 12 upon the rear end of a coupling plate or member 13, the opposite end of which is formed with an inwardly bent right angular flange 14 provided with a screw threaded opening 15. This opening 15 receives an adjusting screw 16, having a headed end 17 projecting outwardly through an opening 18 in the flange 5. If desired, a bearing plate 19 may be secured to the thimble and formed also with an opening for the passage of the screw, by which greater strength and durability will be provided.

As shown, the parts 7, 8 and 16 are disposed in the space 2a provided therefor between the thimble and a portion of the wall 110

of the opening 2, and the head 17 of the member 8 is adapted to engage a locking depression or recess 7' in the pipe 3.

In disposing the parts of the clamping device for the application of the thimble, the adjusting screw is so arranged relatively to the coupling member as to dispose the coupling member and clamping plate in a position substantially parallel with the wall 10 of the thimble, as shown in Fig. 3, thus holding the offset engaging ends of the clamping plate in retracted position and permitting of the application of the thimble. When the thimble is applied the screw may 15 be adjusted to draw the coupling plate outward whereby the clamping plate will be swung outwardly and forwardly at an angle to the thimble, as shown in Fig. 1, so that its head 7 will engage the depression 7' in 20 the pipe 3 and its spurs 10 the wall of the opening 2, thus binding and locking the thimble against either inward or outward movement and also binding and locking the pipe 3 against movement in any direction, 25 whereby casual displacement of the parts will be obviated. It will be observed that this result is secured by means of a simple construction of clamping device which may be easily and conveniently applied, inex- 30 pensively manufactured, and which in operation will efficiently serve to perform its intended function.

I claim:—

1. In a stove pipe anchor, the combination of a stove pipe, a thimble body, having a flange at one end thereof, a clamping plate pivotally mounted upon the body for swinging movements and having clamping por-

tions to respectively engage the stove pipe and the wall of a flue opening, and means 40 for externally adjusting said clamping device to swing the same to clamping and non-clamping position.

2. In a stove pipe anchor, the combination of a stove pipe, a thimble comprising a 45 body having a flange at one end thereof, a clamping member pivotally mounted upon the thimble body for movement into and out of clamping engagement with the wall of a flue opening and the stove pipe, a coupling 50 member connected with said clamping member, and an adjusting device extending through the flange of the thimble and connected with said coupling member.

3. In a stove pipe anchor, the combination 55 of a stove-pipe, a thimble having a T-slot and a flange, a clamping plate having an offset T-shaped clamping member at one end pivotally engaging said thimble, said member being adapted for engagement with the 60 stove pipe and the opposite end of said clamping plate being provided with spurs for engagement with the wall of a flue opening, a coupling member detachably connected with the clamping plate, and an adjust- 65 ing screw engaging said coupling member and extending outward through the flange, whereby said clamping plate may be ad- justed.

In testimony whereof I affix my signature 70 in presence of two witnesses.

ASA FRANK HOUCK.
